COMBINATION CASING HEAD AND BLOW-
OUT PREVENTERGranville A. Humason and James A. Logan,
Houston, Tex.

Application January 3, 1930. Serial No. 418,371

4 Claims. (Cl. 255—1)

This invention relates to new and useful improvements in a combination casing head and blow-out preventer.

One object of the invention is to provide apparatus of the character described for forming a fluid tight joint between the upper end of the casing set in a well bore and an inner pipe or tubing in the bore. The apparatus may be used for forming a blow-out preventer, in drilling, when gas pressure is encountered in the well, or may be employed for forming a fluid tight joint between the pump tubing and the casing, while pumping a well, or for forming a fluid tight joint between an inside pipe and the casing while swabbing or blowing the well; in short the device may be used at the top of the well casing for forming a blow-out preventer, or fluid tight joint between the casing and an inside pipe, or tubing, for any purpose in the well.

Another object of the invention is to provide a device of the character described that may be readily attached to or detached from the casing, and which may also be utilized for sustaining the drill stem from the casing.

With the above and other objects in view this invention has particular relation to certain novel features of construction, operation and arrangement of parts an example of which is given in this specification and illustrated in the accompanying drawings wherein:

Figure 1 shows a side elevation, partly in section, of the apparatus as applied in use.

Figure 2 shows a cross sectional view taken on the line 2—2 of Figure 1.

Figure 3 shows a side elevation, partly in section, of the apparatus as detached from the casing head proper.

Figure 4 shows a plan view thereof, and Figure 5, shows a fragmentary sectional view taken on the line 5—5 of Figure 3.

Referring now more particularly to the drawings, wherein like numerals of reference designate similar parts in each of the figures the numeral 1 designates the casing set in a well bore and having a head 2 screwed thereon provided with one or more outlet lines, as 3. As illustrated there is a tubular drill stem, shown in the casing, whose sections 4 are shown connected by the long polygonal, tubular couplings 5. The drill stem may be rotated by any type of rotary drilling machine and is operatively connected therewith by means of a grief stem, of well known construction, attached to the upper end of the drill stem.

Screwed into the upper end of the head 2, by

left hand threads 6, there is a tubular housing 7 which has an inside, inwardly projecting ring 8 screwed up into the lower end thereof. Fitted within the housing 7 and resting on said inwardly projecting ring 8 there is a packing sleeve designated generally by the numeral 9 and whose ends are anchored to the upper and lower ferrules 10, 11. Each ferrule 10, 11 has an annular row of perforations, or keyways, as 12, 13 therethrough, through which the material, as rubber, of the packing sleeve proper is moulded, and the outer ends of said key ways terminate in the annular end channels, as 14, 15 into which the material of the packing dovetails, as moulded to securely anchor said ferrules in place.

Surrounding the sleeve 9 there is a sleeve like bearing ring 16 whose lower end is seated in an internal, annular raceway 17, in the housing 7. Roller bearings 18 are disposed between the ring 16 and the housing 7. The inside of the ring 16 converges upwardly and thus conforms to the external upwardly taper of the sleeve 9.

Screwed into the upper end of the housing 7 there is a gland 19 having the internal annular flange 20 which overlaps the ring 16, and interposed between said ring and flange there are the antifriction bearings 21.

Within the gland 19 and screwed onto the upper end of the packing sleeve 9 there is spider 22 whose inner side is flush within the inner side of said sleeve 9, and thus fits around the coupling 5, and whose lower end abuts the flange 20. This spider has an external annular groove 23 there around and a set screw 24 is threaded through the gland 19 and projects into said groove and prevents the detachment of the spider and packing sleeve 9 from the assembly. The spider 19 has an upwardly flared seat 25 to receive the wedge shaped slips 26, for a purpose to be hereinafter stated.

In drilling the slips 26 are not used and the drill stem 4 is rotated in the usual way from the rotary drilling machine. The upper joint of said drill stem is commonly known as the kelly joint, or grief stem and is of the same cross section contour as the coupling 5. While drilling this kelly joint is in operative connection with, and is driven by, the rotary table of said machine, and the packing sleeve 9, the bearing ring 16, and the spider 22 rotate with the stem. In case gas pressure is encountered the apparatus described will act as a blow out preventer to prevent the gas from blowing out, unrestrained, around the drill stem, and said gas may be controlled and relieved from the well through one or both of the

95

105

110

lines 3. When it becomes necessary to add another section to the drill stem the stem may be elevated and the kelly joint broken out and the added section screwed into the top coupling 5 and the kelly joint then reattached to the upper end of the added section and drilling proceeded with. While this new section is being made up into the stem, as above explained, the stem should be so located that a coupling 5 will be through 10 the packing sleeve 9 to prevent the escape of gas while the said connections are being made.

When it is desired to withdraw the drill stem from the bore the keys 27, may be inserted into registering keyways 28 between the gland 19 and the spider 22 and upon turning the stem to the right the housing 7 will be turned with it and unscrewed from the head 2 and upon the withdrawal of the stem from the bore, the drill bit will engage the lower end of the packing sleeve 20 9 and lift the preventer apparatus off with it. During this operation the slips 26 should be placed in the seat 25 so as to catch the stem in case it should be accidentally dropped.

In case it is desired to pump the well, the 25 pump tubing may be substituted in the place of the stem 4, or in case there is sufficient pressure in the well to cause the well to flow without pumping a flow line may be substituted for the drill stem 4, and the well then swabbed, in the 30 usual manner, to start the flow of the oil; such pump tubing, or flow line will usually have the sections thereof connected by cylindrical couplings, rather than polygonal couplings and in such case the sleeve 9 and spider 22 should be 35 formed to fit snugly around the coupling. When the flow line or pump tubing is located in the well the upper coupling thereof should be located in the sleeve 9 and the apparatus will then act as a casing head and the oil will be delivered by 40 the pump or flow line to the ground surface while the gas pressure may be relieved through the line, or lines 3.

The slips 26 may be used in suspending the 45 flow line or pump tubing, at a selected location in the well and may also be used for suspending the drill stem in case it be desired to use the same for such purpose.

The drawings and description disclose what is now considered to be a preferred form of the 50 invention, by way of illustration only while the broad principle of the invention will be defined by the appended claims.

What we claim is:

1. A casing head and blow out preventer for 55 forming a seal between an outer casing and an inner tubular string within said casing, and including a tubular housing on the upper end of

the casing and having an inside seat, a gland on said housing, having an inside annular flange, a packing sleeve in said seat and formed to surround said string, a bearing ring beneath said flange around said sleeve, a spider associated with the housing above said sleeve and formed to surround said string, said gland and spider being provided one with an annular groove and the other with a projection which works in said groove.

2. A casing head and blow out preventer for forming a seal between an outer casing and an inner tubular string within said casing, and including a tubular housing mounted above the upper end of the casing, a bearing ring in the housing, said ring and housing having an inside seat, a packing sleeve in said seat and formed to surround said string, a spider associated with the housing above, and connected to, said sleeve and formed to surround said string, said spider having a downwardly converging slip seat around said string.

3. A casing head and blowout preventer for forming a seal between a casing in a well bore and an inner tube in the casing formed of sections connected by enlarged couplings; a housing at the upper end of the casing, a packing sleeve in the housing, a retainer at the upper end of the housing above said sleeve, said sleeve and retainer being formed to fit closely about one of 105 said couplings, a bearing ring in the housing around said sleeve, said retainer, sleeve and ring being rotatable independent of the housing.

4. A casing head and blowout preventer comprising a tubular head on the upper end of a well 110 casing, a tubular housing detachably secured to the head and having the inside raceway, a sleeve like bearing ring whose lower end is seated in said raceway, roller bearings between the ring and housing, a packing sleeve within and surrounded by said bearing ring, a gland screwed within the upper end of the housing and having an inside annular flange which overlaps said bearing ring, a tubular spider within said gland whose inner side is flush with the inner side of said 120 packing sleeve, said spider abutting the upper end of said sleeve, an annular abutment carried by the housing and abutting the lower end of said packing sleeve, said gland and spider being provided one with an annular groove and the other with a projection which works in said groove, whereby the gland and spider are permitted to rotate independently but are retained against separation.
